COMPOUND BED COVER

Evelyn Lehigh, Mamaroneck, N. Y.

Application July 9, 1947, Serial No. 759,840

3 Claims. (Cl. 5—334)

1

This invention relates to bed coverings and has for its general object to provide a compound covering comprising two washable covers and a washable casing or spread which can be used separately as a complete covering independently of the other, or which can be used in various combinations to provide single coverings of varied warmth.

The more particular objects of the invention, as well as the novel features of construction of the compound covering of this invention, will best be understood from the following description when read in connection with the accompanying drawings which illustrate the forms my invention may take in coverings for babies and in which Fig. 1 is a top plan view of a baby's spread embodying my invention; Fig. 2 is a top plan view of a pair of quilts which may be utilized with the spread of Fig. 1 in accordance with the invention; Fig. 3 is an enlarged, broken detailed view of the top edge of the spread, one of the ruffles being partially turned down to show its construction more clearly; Fig. 4 is a plan view showing the appearance of the article when the spread and quilts of Figs. 1 and 2 are combined into a compound covering; Fig. 5 is a sectional view of the spread, taken along the line 5—5 of Fig. 1; Fig. 6 is a sectional view of the compound covering taken along the line 6—6 of Fig. 4; Fig. 7 is an enlarged, broken view of the top edge of a modified form of spread; Fig. 8 is an enlarged, broken view of a pair of modified quilts to be used with the spread of Fig. 7; Fig. 9 is a similar view showing the spread and quilts of Figs. 7 and 8 combined into a compound cover and Fig. 10 is a sectional view taken along the line 10—10 of Fig. 9.

In the drawings, the numeral 10 designates the spread of the compound covering which may be utilized separately as a light covering for a baby or as a casing for the cover members 11 and 12, which may be in the form of washable blankets, quilts, puffs or comforters, and which may be combined with such spread in the manner hereinafter described to obtain coverings of varied weight and warmth. The spread 10 is composed of two layers 13, 14 which may be made of any suitable material, such as organdy, and which are united along their side and bottom edges to form a casing approximately three feet wide and four feet long. As is shown more clearly in Fig. 5 of the drawings, each of the layers 13 and 14 is double folded inwardly along its side and bottom edges and is seamed to corresponding edges of the other layer by two lines of stitches 15 and 16

2

which also secure to such folded edges of the layers, a ruffle 17. The upper or top edge of each of the layers 13, 14 is folded inwardly and outwardly to form a relatively wide three ply fold 18. Provided on the inner surfaces of the folded edge portions 18, 18 are suitable complementary fastening devices, generally indicated by the numerals 19, 19 for securing such edge portions together. The fastening devices may comprise buttons, clasps, snap fasteners, or the like, but preferably are slide fastener stringers whose interlocking elements are opened or locked in interfingered relation by means of a manually operated slider 20 in the manner usual with such fasteners. As is shown in Fig. 1 of the drawings, the slide fastener structure may extend from one corner of the casing formed by the layers 13, and 14, and along the top edge portions 18, 18 to a point short of the other ends of such portions, but along a sufficient length of such edge portions to permit ready entry into the casing or spread 10 when the slider is completely opened. It will be noted from Fig. 6 of the drawings, that the stringers 19, 19 of the fastener structure are positioned on the folded edge portions 18, 18 so that the interlocking elements are positioned just above the top edge of such portions. The stringers 19, 19 are partially secured to the edge portions 18, 18 by means of lines of stitches 21, 21 which extend through the material of such stringers and through the material of such edge portions along lines adjacent to the upper edges of such portions 18, 18. The stringers 19, 19 are also secured to the edge portions by means of lines of stitches 22, 22 which penetrate such stringers along lines adjacent to the lower edges thereof. The lines of stitches 22, 22 also penetrate through and secure to the edge portions 18, 18, the ruffle pieces 23, 23 and the strips of decorative material 24, 24, such lines of stitches 22, 22 extending along the upper edges of the strips 24, 24. The lower edges of the strips 24, 24 are substantially even with the lower edges of the folded edge portions 18, 18 and the two in each layer are secured together by the lines of stitches 25, 25. It is to be noted that the lines of stitches 21, 21 beyond the ends of the stringers 19, 19 secure the upper edges of the edge portions 18, 18 together and function as means to prevent possible separation of the ends of the stringers beyond the interlocking elements of such stringers due to usage of the slider 20. The stitches 21, 21 also serve to secure at the ends of the top edge portions, a pair of depending tabs 26, 26 which may be further secured in position by additional short

lines of stitches penetrating the top folds of both layers 13 and 14. Each tab 26 is provided with a pair of complementary fastening devices such as the male snap member 27 and the female snap member 28, shown more clearly in Fig. 6 of the drawings.

The cover members 11 and 12 are each preferably, although not necessarily, made in the form of quilts. When made in the form of quilts, the members 11 and 12 are each preferably composed of outer layers of any suitable washable material such as silk, satin, rayon, chintz, etc. and are stuffed with a washable fiber material, such as lamb's wool; the whole being united by quilting stitches in the usual fashion. Secured to the ends of the upper edges of the quilts 11 and 12, are pairs of upwardly projecting tabs 29, 29 and 30, 30, respectively, each being provided with complementary fastening devices adapted to interlock with one or both of the fastening devices 27 and 28 of the spread 10. It will be observed from Fig. 6 of the drawings, that the fastening devices on the tab 30 of the quilt 12 are reversed in position with relation to the fastening devices on the tabs 26, 26 of the spread 10. Thus, on each of the tabs 30, 30, of the quilt 12, the male snap fastener 31 is positioned below or inwardly of the female snap fastener 32, while on the depending tabs 26, 26 of the spread 10, the male snap fastener 27 is positioned above the female snap fastener 28. On each of the tabs 29, 29 of the quilt 11 there is provided but one fastener element, the female snap fastener 33.

It will be understood from the foregoing that each of the parts 10, 11 and 12, may be used separately; the spread 10 when used alone, serving as a light summer covering for the baby, while the quilts 11 and/or 12 may be used when additional warmth is required. In such single use of the spread 10 and the quilts 11 or 12, the complementary snaps on each tab thereof, are preferably interlocked, so as to reduce the size of the tabs and possible injury to the baby. Preferably also, the slider 20 of the fastener on the spread 10 has been moved to its fully closed position to cover the projecting ends of the elements on the stringers 19, 19; the ruffles 23, 23 along the top edge of the spread concealing the closed fastener structure and preventing any possibility of the baby being scratched or otherwise injured by the same. Either one of the quilts 11 or 12 may be used with the spread 10 by inserting such quilt within the spread and interlocking the male snaps 27 of the spread with the female snaps of the inserted quilt and in the case of quilt 12 by also interlocking the female snaps 28 of the spread with the male snaps 31 of such quilt. If it is desired to use the two quilts 11 and 12 together as a unit, the complementary male and female snaps on the ends of such quilts are interlocked together. When maximum warmth is required, the snaps are interlocked in the manner shown in Fig. 6 of the drawings. In such use of the covering, the female snaps 33 of quilt 11 are interlocked with the male snaps 31 of quilt 12 and the female snaps 32 of quilt 12 are interlocked with the male snaps 27 of spread 10.

It will be noted that whenever two or three of the parts 10, 11 and 12 are secured together in the manner previously described, the resulting compound covering in which the quilts 11 and 12 in effect constitute a lining for the spread 10, can be handled as a single covering, by grasping the top edge of such compound covering and laying it on the child. This facilitates the covering

of the child and enables the several layers of the compound covering to be laid smoothly and evenly on the child with a minimum of effort. Besides the ease of handling and the varied conditions of temperature which can be taken care of by the compound covering, the latter also possesses the advantages that its separate parts can be readily disassembled and cleaned and that when the quilts 11 and/or 12 are contained within the spread 10, they are kept clean and free from contamination by dirt.

While I have hereinabove described a preferred embodiment of my invention, it will be apparent to those in the art, that various changes and modifications may be made therein without departing from the spirit of the invention. For example, instead of providing the spread 10 and quilts 11 and 12 with snap fasteners, these members may be provided with separable slide fasteners to obtain the results desired. This construction is shown in Figs. 7 to 10 of the drawings in which the spread and quilts illustrated are made similar to those shown in Figs. 1 through 6 of the drawings, but differ in regard to the following details. Layer 14' of the modified spread 10' is shown provided with a fastener stringer 35 similar to stringer 19 on the layer 14 of spread 10. Layer 13' of spread 10' however, has mounted thereon, a stringer 36 which is provided with a series of interlocking elements along both its top and bottom longitudinal edges. The upper series of interlocking elements on stringers 36 is adapted to be interlocked with the elements on stringer 35 by means of the slider 20' in the manner previously described. The lower series of interlocking elements on stringer 36 form part of a completely separable fastener, the slider 37 of which is permanently mounted on the lower series of interlocking elements on stringer 36, and which may include either the series of complementary fastener elements on stringer 39 attached to the upper edge of quilt 11' or the series of fastener elements attached to the upper edge of a stringer 38 secured to the upper edge of quilt 12'. It will thus be seen that either of the quilts 11' or 12' may be attached to the spread 10' by causing the interengagement of the locking elements on the lower edge of stringer 36 with either the locking elements on stringer 39 or the locking elements along the upper edge of stringer 38, through manipulation of the slider 37. The stringer 38 may also form part of a completely separable fastener composed of such stringer, the series of interlocking elements provided along the lower edge of stringer 39 and the slider 40 which is permanently connected to such elements on stringer 39. By this construction, the two quilts 11' and 12' may be connected together as a separate compound covering, or the two quilts may be connected with the quilt 10' in the manner shown in Fig. 9 of the drawings to form a compound covering including all three parts. This construction in addition to possessing the advantages previously described with respect to the parts provided with snap fasteners, also enables the parts to be connected along the entire lengths of their upper edges, thereby facilitating handling and smooth laying of the compound covers.

I claim:

1. A compound covering comprising a casing having its top edges separable to permit entry therein and constituting a complete quilt and adapted to be used alone as such, a covering member likewise constituting a complete covering be-

ing removably positioned within said casing and of such dimensions as to be substantially equal in area to the area of the enclosing sides of said casing, said casing having along its top edges complementary fastening devices for securing said edges together when said casing is used either alone or with the covering member contained thereon, a border of textile material projecting outwardly from the edges of said casing and along the top edges of the latter concealing said complementary fastening devices, additional fastening devices mounted on the top edges of said casing and wholly contained within the confines of such casing below said complementary fastening devices, and cooperating fastening devices mounted on the top edge of said covering member and adapted to be interlocked with the fastening devices within said casing to form a compound covering.

2. A compound covering comprising a casing having its top edges separable to permit entry therein and constituting a complete quilt adapted to be used alone as such, complementary fastening devices provided on the top edges of said casing for securing said edges together when the casing is used alone or with a covering member contained therein a ruffle projecting outwardly from the edges of said casing and along the top edges thereof concealing said complementary fastening devices and supporting means connected to the interior top edge portion of said casing and depending downwardly therefrom within the casing to a point substantially below said complementary fastening devices and additional fastening devices mounted on the pendant portions of said supporting means and adapted to cooperate with fastening devices provided on a covering member to support the latter within said casing.

3. A compound covering comprising a casing having its top edges separable to permit entry therein and constituting a complete quilt adapted to be used alone as such, a covering member likewise constituting a complete covering and a second covering member likewise constituting a complete covering, said covering members being removably positioned within said casing and each being of such dimensions as to be substantially equal in area to the area of the enclosing sides of said casing, said casing having on its top edges complementary fastening devices for securing said edges together when said casing is used alone or with either or both of the cover members contained therein, additional fastening devices mounted on the top edge portions of said casing and wholly contained within the confines of the latter below said complementary fastening devices, fastening devices on the top edge of at least one of said covering members cooperable with the additional fastening devices within said casing, and a second set of complementary fastening devices mounted on the top edges of said covering members for securing said covering members together whereby said covering members will be connected together at their top edges by said second set of complementary fastening devices and will be supported as a unit by said additional fastening devices.

EVELYN LEHIGH.
